L. O. Gillies.

INVENTOR
Gabriel E. Rohmer

UNITED STATES PATENT OFFICE.

GABRIEL E. ROHMER, OF NEW YORK, N. Y.

CONSTRUCTION OF SWIMMING-POOL WATER SLIDES.

Application filed March 30, 1925. Serial No. 19,390.

While I am aware that slides are used by bathers and swimmers, no apparatus has come to my attention which as a constant stream of water spraying the slide surface of 5 the apparatus; therefore the object of the present invention is to provide a water slide, embodying means which will allow a relatively thin stream of water to constantly spray the sliding surface of the slide, the 10 water spray furnishing the sliding means impinging the body of the bather in rapid downward sliding motion.

With these objects in view, my invention comprises the novel features, combinations 15 and arrangements of parts, hereinafter more fully described, with reference to the accompanying drawings in which Figure (1) is a cross section elevation of a preferred type of my water slides. Figure (2), its plan view, 20 while Figures (3 and 4) illustrate the water slide trough embodying a different method of spraying the water on the sliding surface of the trough itself.

Similar reference numbers indicate corresponding parts throughout the different 25 figures.

Figures (1 and 2) illustrate the cross section and plan view of a water slide built like a trough. 30 To facilitate the erection of the apparatus, the trough is preferably made in unit lengths (1—2—3—4 and 5). The combination of those unit lengths being appropriately designed to form a sliding curved surface best 35 adapted to impinge a sliding body in a rapid downward sliding motion.

The longitudinal sides (6 and 7) of the water slide are curved inwardly, thus forming a trough of appropriate shape, adapted 40 to act as a safety guide to the rapidly moving body of the bather.

The top section of the water slide (1), properly supported on top of the column (8), has an overflow water trough (9) running 45 the full width of the apparatus. In this overflow water trough is cut a longitudinal opening (10), forming the outlet of the water stream spraying the sliding surface (11). At one side the pipe (12) is 50 provided as means for bringing the water supply to the overflow trough, while the valve (13) affords means for regulating the intensity of the overflow.

The top section of the water slide (1) is 55 also provided with a flat surface (14), im-

mediately adjacent to the water trough, but of a level relatively higher than the overflow outlet of the water trough; this flat surface acts as a dam for the overflow stream and is also intended as a rest platform, enabling the bather to engage his body in the trough with the least possible exertion. 60

A platform (15) surrounded by the protecting rails (16), is arranged at the base of the water slide section (1) at a height conveniently calculated to enable the bather to easily overbalance his body into the sliding trough, while the ladder runs (17) permit access to the platform. 65

The sections (2—3 and 4) forming the 70 runs of the water slide have rubber gaskets (18) bolted in-between the flange joints (19) to insure the perfect waterproofing of the apparatus and the base (5) is provided with outlet means leading the water flow into the 75 pipe (20) to a waste water outlet.

In order to promote an easy outgoing flow of the waste water, the base unit (5) has an inclined surface (21) leading to a flat funnel shaped duct (22). This duct can also be 80 used as an overflow for the water contained in the swimming pool (23) near which my water slides will preferably be erected.

In Figures (3 and 4), I have illustrated another embodiment of my invention showing a different method of spraying the sliding surface of my apparatus. In this case, the pipes (24) are located within each upper rounded edge (6 and 7) of the trough (25) and run the full length of the water slide. 85 The holes (26) are conveniently located along the length of the pipes to furnish a well fed stream of water on the sliding surface (11).

I favor most particularly the type of construction illustrated in the drawings, making the whole structure self supporting through the flanges (19), thus eliminating structural shape frames commonly used in dry slides in children's play grounds. 90

In Figure (1) I have illustrated how my water-slide is used by bathers; reference number (27) showing a bather overbalancing himself over the top of the water slide, while reference number (28) illustrates another bather in the act of sliding down under the slippery action of the water stream discharged by the trough (9). 105

I have illustrated two preferred and satisfactory forms of my invention, but it is ob- 110

vious that changes may be made, and embodiments evolved which would still be within the spirit and scope thereof as defined in the appended claims.

I claim:

1. In a water slide, in the form of a trough, an overflow duct at the high point of said water slide and means for draining the overflow water at the bottom of said water slide.

2. In a water slide, in the form of a trough, means provided within each upper longitudinal edge of said water slide adapted to induce a water stream on the sliding surface of said water slide, and means for draining said water stream at the bottom of said water slide.

3. A water slide built in sections, overflowing means in the upper section, intermediate sections forming the run of said water slide and a base section, said base section having drainage means.

4. A water slide built in sections, overflowing means in the upper section, intermediate sections forming the run of said water slide and a base section having drainage means; each of said sections being provided with connecting flanges substantially strong enough to support the full weight of said water slide.

5. A trough for a water slide comprising a flat sliding portion, and two upward portions, said upward portion being curved inwardly and affording safety guiding means for bathers.

6. In a water slide an upper member having overflowing means for a fluid flow and a flat surface above said overflowing means, said flat surface acting as a dam for said fluid flow.

7. In a water slide an upper member having overflowing means for a fluid flow and a flat surface above said overflowing means, said flat surface acting as an over-balancing starting point for bathers.

8. In a water slide built in sections, overflowing means in the upper section, means for regulating the intensity of the fluid flow,

intermediate sections forming the run of said fluid flow and a base section.

9. In a water slide built in sections, overflowing means in the upper section, means for regulating the intensity of the fluid flow, intermediate sections forming the run of said fluid flow and a base section, said base section having drainage means.

10. In a water slide an upper member having overflowing means for a fluid flow, a flat surface above said overflowing means, said flat surface acting as an over-balancing and starting point for bathers and platform means adjacent said upper member.

11. In a water slide an upper member having overflowing means for a fluid flow, a flat surface above and adjacent said overflowing means, said flat surface acting as an overbalancing and starting point for bathers and platform means adjacent said upper member, said platform means being located below said overbalancing flat surface.

12. A water slide comprising a trough and a platform, means to induce a fluid flow along the entire sliding surface of said trough, means for regulating the intensity of the flow and means for evacuating the flow, said platform being adjacent to the upper end of the trough and acting as an overbalancing and starting point for bathers.

13. A water slide comprising a trough and a platform, means to induce a fluid flow along the entire sliding surface of said trough, means for regulating, localizing and draining said fluid flow, said platform being adjacent to the upper end of the trough and acting as an overbalanceing and starting point for bathers.

14. A water slide comprising a platform and an inclined trough, means to induce, regulate, dam and drain a fluid flow within the sliding surface of said trough, the platform being adjacent to the upper end of the trough and acts as an overbalancing and starting point for bathers.

In testimony whereof I affix my signature.

GABRIEL E. ROHMER.
